UNITED STATES PATENT OFFICE

JOHN S. BARNES, OF ROCKFORD, ILLINOIS, ASSIGNOR TO W. F. AND JOHN BARNES COMPANY, OF ROCKFORD, ILLINOIS, A CORPORATION OF ILLINOIS

DRILLING MACHINE

Application filed February 18, 1925. Serial No. 9,912.

The primary purpose of this invention is to provide an improved production drilling machine, so called because it is especially designed for continuous or heavy duty work as is required in certain shops where large quantities of parts are to be drilled. The machine is not, however, limited to drilling but is adapted also for tapping and boring.

Another purpose of my invention is to provide a drilling machine of this kind which will have a large capacity as regards drill sizes, speeds and feeds, in comparison with its size.

A further purpose is to provide improved means for mounting and driving the tool spindle, whereby to eliminate as much as possible tool chatter and torsional and lateral stresses in the spindle with a view to maintaining alignment thereof under all conditions and to insure a fine degree of accuracy and precision in drilling. In other words by reason of these improvements the machine will produce accurate drilling within its capacity under continuous duty operation where heretofore with prior machines intended for this purpose the desired degree of accuracy in drilling alignment has been difficult to obtain because of faulty machine construction which imposed undue torsional and lateral stresses on the spindle, its bearings and driving parts, resulting in unequal wear and consequent deflection of the spindle.

Still another purpose of my invention is to provide improved spindle feed and speed mechanism characterized by gearing arranged in a particularly novel and advantageous manner in a single housing, thereby promoting simplicity and compactness of parts, economy in the cost of production of these machine, and the facility for lubricating from a single source all of the gears and the various bearings.

Other objects and attendant advantages will be appreciated by those skilled in this art as the invention becomes better understood by reference to the following description when considered in connection with the accompanying drawings, in which:

Figure 1, is a side elevation of a drilling machine embodying my invention;

Fig. 2, is a front elevation of the upper portion only of the machine;

Fig. 3, is a vertical section through the head taken substantially on the line 3—3 of Fig. 2;

Figs. 4, 5 and 6, are sections taken on the lines 4—4, 5—5 and 6—6, respectively, of Fig. 3; and

Figs. 7 and 8, are sections taken on the lines 7—7 and 8—8, respectively, of Fig. 2.

Frame construction

My invention is embodied, preferably but not necessarily, in an upright drilling machine having a suitable base 11, an upright box-section pedestal or column 12 thereon, a suitable work table 13 vertically adjustable on the column, and a head or top-housing designated generally by 14 rigidly secured to the top of the column 12.

The top-housing is preferably a one-piece casting providing a gear-box or casing 15 directly above the column 12 and a spindle housing 16 overhanging the work table, with the exception that cover plates 17 and 18 are provided over the opening in the top of the gear-box and front of the spindle housing, respectively, for access to the parts therein. It will be noted as the description progresses that the spindle and all of the bearings therefor and the various gear shafts are supported in this one-piece head or housing in a compact and novel arrangement the purposes and advantages of which will be hereinafter described.

Spindle mounting

According to my invention the spindle is journaled and supported in an upper and a lower bearing at the top and bottom of the spindle housing so as to provide a maximum length of bearing. The spindle itself, designated generally by 19, is in the form of a cylindrical bar of relatively large diameter, which bar slides in and is guided by the lower bearing and has a socket (not shown) in its lower end for reception of a tool or tool-carrying chuck. The upper end 21 of the spindle is reduced in diameter and revolves in suitable bearings 22 in a non-rotatable sleeve 23 which slides in a bearing 24 in the upper

end of the spindle housing. The sleeve 23 has a rack 25 on its rear face, with which rack a pinion 26 meshes for moving the sleeve and consequently the spindle lengthwise, the pinion being operated by a feed mechanism which will be described later. The spindle is supported on the sleeve 23 by an end-thrust collar 26 adjustably secured to the upper end of the spindle part 21, with a roller thrust bearing 27 interposed between the collar and sleeve, and the opposite or upward end-thrust resulting from the drilling pressure is taken by a roller bearing 28 interposed between the driving end 29 of the spindle proper and the lower end of the sleeve 23.

The spindle proper is splined from end to end and fits in complementary splines in a sleeve 31 which in turn is secured in the hub 32 of a spindle drive gear 33, preferably a bevel gear. The gear hub 32 revolves in a bearing sleeve 34 which is vertically adjustable in the spindle housing 16. An end-thrust ball bearing 35 is interposed between the bevel gear 33 in the bearing sleeve 16. The bevel gear is bored out down to the splined sleeve 31 to permit the lower end of the non-rotatable sleeve 23 to telescope within the gear and thereby increase the feed length in an organization of parts, such as disclosed herein. A suitable bearing 36 is provided in the gear 33 for guiding the lower end of the sleeve 23 and consequently the spindle.

While my invention contemplates broadly an organization of parts, such as disclosed, or their equivalent, attention is directed to the specific construction of such parts, since this is one of the principal contributing factors to the results obtained, especially in regard to maintaining alignment of the spindle. The bore 37 for the bearing sleeve 34 and the bore providing the bearing 24 are machined in a single setting of the spindle housing, with the result that they establish an accurate base for alignment of the upper and lower spindle bearings. The bearing sleeve 34, preferably of bronze, is accurately machined and its bore is reamed. The lower end of this bearing sleeve is externally threaded and screwed into the spindle housing, thus providing a means for axially adjusting the spindle drive gear 33 with respect to its companion pinion 38. The gear hub 32 is accurately finished on its periphery to have a running fit in the bronze bearing sleeve 34, and its bore is reamed to receive and hold in absolutely concentric relation the splined sleeve 31 and the bearing sleeve 36. Said splined sleeve 31, preferably of tool steel, is ground on its periphery, has a press fit in the gear hub 32, and is secured therein by any suitable means such as a woodruff key 39 and one or more set screws 41 between the sleeve and gear hub. The splines in the sleeve 31 are formed preferably by a broaching opera-

tion; and in order that the splines shall be located concentrically within the gear hub 32 and the bearing sleeve 34, to a high degree of precision the periphery of the sleeve 31 is ground on a revolving arbor in true concentric relation to the surfaces 42 of the spline grooves. In other words, when finishing the sleeve 31 it is mounted on an arbor by location of its spline groove surfaces 42 so that when the periphery of the sleeve is ground it will be absolutely concentric with said surfaces. The spindle proper is machined so that its splines 43 accurately fit in the spline grooves in the sleeve 31, both at the ends 44 and at the periphery 45, but leaving a clearance between the bottom of the spindle spline groove 46 and the sleeve splines. As a result of this construction absolute alignment of the spindle will be maintained. In this regard it will be noted that the peripheral surfaces 45 of the spindle bear against the surfaces of the splined sleeve 31 which in turn is accurately supported in concentric relation or axial alignment with the upper and lower spindle bearings. The bearings thus provided are one factor towards maintaining the desired alignment. Another important factor is the location of the spindle-driving splines at the lowermost end of the spindle-housing so as to be close to the work and thus reduce to the minimum torsional stresses in the spindle. Another and most important factor is the provision of three or more equally circumferentially spaced spindle-driving splines or keys, preferably integral with the driving part, in this instance the sleeve 31 which is in effect integral with the spindle-drive gear 33. The advantage of this construction is that the wear on the ends 44 of the splines resulting from the driving pressure will be reduced to a minimum and equalized, thus producing a uniformly distributed driving pressure as distinguished from prior constructions which employ one or two driving-keys which have a tendency to wear unevenly and sooner or later cause unequal driving pressure and consequent distortion or deflection of the spindle. In other words, unless the spindle itself is accurately guided as to alignment and the driving pressure is uniformly and evenly applied, tendencies will arise by reason of variances in lateral pressure and stresses causing either the spindle or the spindle bearings, or both, to wear unevenly, resulting in failure of alignment. Still another advantage of this construction is that by reason of the comparatively large diameter of the spindle proper and of the type of the drive splines, a large lever arm is available in transmitting the spindle driving pressure. Still another advantage from a manufacturing standpoint is the facility with which the spindle may be maintained and guided to a high degree of precision concentrically within a driving-gear. This latter advantage is 130

obtained primarily because of the splined sleeve construction described above, which sleeve is replaceable.

Spindle drive mechanism

5 This mechanism, enclosed and mounted in the gear-box 15, comprises a series of horizontal shafts 47, 48 and 49 arranged in a vertical plane and journaled in suitable bearings in the front and rear walls 51 and 52, respectively, 10 of said gear-box or casing, and change-speed gears connecting these shafts. The lowermost shaft may be driven from any suitable source of power, the present machine being 15 equipped with a drive-pulley 53 connected by bevel gears (not shown) to said shaft. On this shaft is splined a pair of integrally connected spur gears 54 and 55 which are adapted to mesh, respectively, with gears 56 20 and 57 fixed to the shaft 48, said pair of gears being shiftable for this purpose by operation of a hand lever 58 at the control side of the machine, connected through the agency of a yoke-shaped shifter lever 59 and a shifter 25 yoke 61 which fits in a groove intermediate the gears. Two pairs of gears are splined and independently shiftable on the shaft 49. The first pair comprising gears 62 and 63 are 30 adapted to mesh, respectively, with gears 64 and 57 fixed to the shaft 48, and the second pair comprising gears 65 and 66 are adapted to mesh, respectively, with gears 67 and 68 fixed to said shaft 48. Said pairs of gears 62-63 and 65-66 are adapted to be shifted 35 by operation of hand levers 69 and 71, respectively, at the control side of the machine, each hand lever being fixed to a rock shaft 72 mounted in the side walls of the gear-box and having depending arms 73 connected to a 40 shifter collar 74 located in a groove between the gears of its respective pair. By throwing the lever 58 to the right the gears 54 and 56 will be engaged for the low spindle speeds, of which there are four, established progressively by throwing the lever 69 to the right 45 for engaging the gears 62-64, to the left for engaging the gears 63-57, and by throwing the lever 71 to the right for engaging the gears 65-67 and to the left for engaging 50 gears 66-68. Upon throwing the lever 58 to the left to engage the gears 55-57, four higher spindle speeds may be obtained. The spindles speeds are, obviously, selective. Suitable means may be provided for holding either 55 hand lever 69 or 71 against operation when the other has been operated to effect a speed change. At present I employ a locking lever 70 (Fig. 1) pivoted intermediate its ends on the control side of the gear-box and adapted 60 to lock either hand lever from turning when the other has been operated. To this end, the hub of each lever when turned, raises the adjacent lever end and forces the opposite end down into a notch in the other lever hub. 65 It will be noted that the spindle driving pin-

ion 38 above-mentioned, is fixed directly to the uppermost shaft 49 of the spindle speed train. It will also be noted that by arranging the change-speed gear shafts in a vertical plane and journaling them in the front 70 and rear walls of the gear-box, the top housing structure may be made comparatively narrow without imposing limitations on the size of the gears and the length of the gear shafts and, furthermore, this gearing train 75 may be arranged close to the spindle and connected directly thereto. Furthermore, the gear-box constitutes an oil reservoir and oil in the bottom thereof is picked up by a splash wheel 75 on the bottom shaft 47 and by the gears thereon and thrown upwards so as to lubricate all of the gears within the gear box, likewise the shaft bearings and the lower spindle bearing, it being noted that there is an oil conduit or lead 76 from the front bearing of the shaft 48 to the lower spindle bearing, which lead also extends to the bearing sleeve 36 for oiling this and the spindle proper.

Spindle feed mechanism

Power for the spindle feed is transmitted from the uppermost spindle-speed shaft 49 to a set of change-feed gears mounted in the upper forward part of the gear-box 15 and connected with the spindle-feed pinion 26 through the agency of a stop mechanism which may be either hand or automatically operated, as will be presently more fully described.

The change-feed gears referred to are mounted on horizontal shafts 77 and 78 extending transversely to the spindle speed shafts and journalled in suitable bearings in the side walls of the gear-box above the uppermost shaft 49. The feed power is taken from a spiral gear 79 fixed to said shaft 49 and meshing with a companion spiral gear 81 fixed to a sleeve loose on the shaft 77. To this sleeve is also fixed a pair of spur gears 83 and 84 (Fig. 5). Gears 85 and 86 keyed to the shaft 78 and shiftable lengthwise thereon as a unit are adapted to mesh, respectively, with the gears 83 and 84 for changing speed between the sleeve 82 and the shaft 78, a suitable hand lever 87 and shifting lever 88 being employed for shifting said gears. The shafts 78 and 77 are connected by change-gears 89 and 91 which may be either transposed or removed for substitution of gears of different ratio for the purpose of changing the rate of feed with respect to the spindle speed. It will be observed that the bearings 92 for the shafts 77 and 78 are set in from the change-gears 88-91, entirely within the gear-box, and that a suitable cover plate 93 closes the compartment 94 in which said gears are located. When the gears 83 and 85 are in mesh a low feed speed is produced for drilling, and when the gears 84 and

86 are in mesh a high feed speed is produced for reaming.

The end of the shaft 77 remote from the change gears extends beyond the gear-box 5 and has fixed thereto a bevel gear 95 and has mounted thereon a bracket designated generally by 96. In this bracket is journaled a shaft 97 coplaner with and at right angles to the shaft 77 and carrying a loose bevel gear 98 in mesh with the gear 95. Said gear 98 is adapted to be connected to the shaft 97, at will, by means of a manually shiftable clutch collar 99 having a key connection with said shaft, this clutch being shown engaged in 15 Fig. 5. Said shaft 97 also has fixed thereto a worm 101 adapted to mesh with a worm-gear 102 fixed to the feed shaft 103 to which the feed pinion 26, above-mentioned, is likewise fixed. Said worm is adapted to be 20 brought into and out of mesh with the worm-gear by raising and lowering the front end of bracket 96 about its pivotal support on the shaft 77, thus connecting and disconnecting the feed-gear in the gear-box and the spindle 25 feed pinion 26.

Manually operated means is provided for raising and lowering the bracket 96 to engage and disengage the feed, and automatically operated means is provided for disengaging the feed at a pre-determined time, thus providing what is known in this art as an automatic stop. The particular form of automatic stop disclosed herein is more fully described and claimed in my co-pending application Serial No. 464,416, filed April 18, 1921. The manually operated means mentioned comprises a cam element 104, in this instance integral with a hand lever 105, mounted on a rock-shaft 106 at the control 30 side of the machine, said cam element being adapted to bear against a thrust-plate 107 adjustably fastened to the bracket 97 beneath the front portion thereof. Said thrust-plate has two seats 108 and 109 at different elevations connected by an inclined surface, whereby upon oscillating the lever 105 in a counter-clockwise direction viewing Fig. 8, the cam element 104 will be withdrawn from the seat 108 so as to allow the bracket 96 to drop and 40 unmesh the worm 101, the lower position being limited by contact of said cam element against the seat 109. Reversal of this operation raises the worm into mesh with the worm gear 102. The automatic stop comprises an arm 111 fixed to the rock-shaft 106, a link 112 pivoted at one end to said arm and at its opposite end to a follower 113, a spiral groove 114 in the worm-gear body 102, in which groove the follower 113 is located, and a stop 50 element 115 adjustable to any position along the length of said groove and adapted to actuate said follower by rotary motion of the worm gear in a counter clockwise direction viewing Fig. 1, thereby unmeshing the worm 60 gear and stopping the feed, as will be obvious.

The feed may also be operated directly by hand by radial hand bars 116 on the feed-shaft 112, or by a hand-wheel 117 fixed to the worm shaft 97 and adapted to be operated when the clutch 99 is disengaged.

In order to counterbalance the spindle I have provided a spiral spring 118 (Fig. 7) attached at one end to an enclosing casing 119 in turn secured to the feed shaft 103 by a clamp 121, the spring being attached at its 70 opposite end to a fixed part such as a boss 122 in the spindle housing. It will be manifest that as the spindle is fed down the spiral spring 118 will be tightened and that the stored-up spring pressure will be utilized to aid in returning or elevating the spindle.

From the foregoing it will be manifest that when either the gear 85 or 86 is engaged with its companion gear and the clutch 99 and worm drive are engaged, the feed pinion 26 85 will be revolved by power simultaneously with rotation of the spindle by the spindle-drive mechanism above described, the spindle speed and feed being determined by the particular gears in mesh in the respective change-gear trains.

It is believed that the foregoing conveys a clear understanding of the principles of my invention and of the objects prefaced above, and while I have illustrated and described 95 but a single working embodiment it should be understood that many changes might be made in details of construction and in the arrangement of parts within the scope of the present invention, expressed in the appended 100 claims, in which—

I claim:

1. In a drilling machine, in combination, a spindle housing having spaced coaxial bores, a bearing sleeve axially adjustable in one of said bores, a spindle drive gear the hub of which is journaled in said bearing sleeve, an internally splined sleeve fixed in said gear hub, a tool spindle one end of which is splined in said splined sleeve and the other end passes through the other housing bore, a non-rotatable sleeve in which said other end of the spindle is journaled and which is guided in said other bore, and means engaging said non-rotatable sleeve for imparting feed movement to the spindle.

2. A drilling machine as set forth in claim 1, in which the spindle drive gear has an elongated hub at the end remote from the non-rotatable sleeve and has a bore at its 120 opposite end of sufficient diameter to allow said non-rotatable sleeve to telescope within the gear hub.

3. In a machine tool, in combination, a spindle housing having an internally threaded bore, a bearing sleeve fitting in said bore and threadedly engaged with the screw threads therein so as to be axially adjustable, a bevel gear the hub of which is journaled 125 in said bearing sleeve and the toothed body of 130

which is located beyond one end thereof, a bevel pinion journalled in the housing and meshing with said bevel gear, an anti-friction end-thrust bearing interposed between the bevel gear body and the adjacent end of the bearing sleeve, a tool spindle telescoping within and driven by said gear, and means for imparting axial feed movement to the spindle.

10. 4. In a machine tool, in combination, a spindle housing having spaced coaxial bores, a bearing sleeve secured in one of said bores and having an accurately finished internal bearing surface, a spindle drive gear the hub of which has a running fit in said sleeve bearing and the internal face of which is accurately finished, an internally splined sleeve the periphery of which is finished concentrically with respect to the bottom surface 15 of the splined grooves therein, said spline sleeve having a press fit in the gear hub, a tool spindle the tool-carrying end of which is splined and fits in said spline sleeve, the splines on the spindle having peripheral lateral bearing and end driving bearing against 20 complementary faces of the sleeve spline grooves and the opposite faces of the sleeve splines, a non-rotatable sleeve in which the opposite end of the spindle is journalled and 25 which is slidably guided in the other bore of the housing, and means engaging the non-rotatable sleeve for imparting feed movement to the spindle.

5. In a machine tool, the combination set forth in claim 4, in which the spindle drive gear is in the form of a bevel gear located intermediate said bores in the housing, and including a bevel pinion journalled in the housing and in mesh with said bevel gear, and 30 means for axially adjusting said bearing sleeve in the housing for maintaining the bevel gear in proper mesh with its pinion.

6. A machine tool as set forth in claim 4, in which the spindle drive gear has an elongated hub and the spline sleeve therein is 35 located at the end of the hub remote from the non-rotatable sleeve, and a bearing in the opposite end of the hub within which the non-rotatable sleeve is adapted to telescope 40 and which provides lateral bearing support 50 for said sleeve.

JOHN S. BARNES.
